UNITED STATES PATENT OFFICE

170,150

BIRD FEEDER OR SIMILAR ARTICLE

Henry B. Cowap, Evanston, Ill.

Application September 17, 1952, Serial No. 21,508

Term of patent 14 years

(Cl. D31—2)

To all whom it may concern:

Be it known that I, Henry B. Cowap, a citizen of the United States of America, residing in Evanston, Illinois, have invented a certain new, original, and ornamental Design for a Bird Feeder or Similar Article, of which the following is a specification, reference being had to the accompanying drawing, forming a part hereof.

The figure is a perspective view of a bird feeder or similar article, showing my new design.

I claim:

The ornamental design for a bird feeder or similar article, substantially as shown.

HENRY B. COWAP.
